TENTERING CLIP

Filed July 10, 1930

Inventor,

John E. Peterson,

By his Attorney

John E. Peterson

UNITED STATES PATENT OFFICE

JOHN E. PETERSON, OF IRVINGTON, NEW JERSEY, ASSIGNOR TO VAN VLAANDEREN MACHINE COMPANY, OF PATERSON, NEW JERSEY, A CORPORATION OF NEW JERSEY

TENTERING CLIP

Application filed July 10, 1930. Serial No. 467,012.

This invention relates to the endless flexible traveling cloth-gripping structures of a tentering machine, and its object is to produce a structure of this class which shall be lighter, stronger and more durable than others of its class heretofore known and which will have its points of flexion closer together so that it will operate more smoothly and with less wear than the known structures. Some of the features of difference between the structure of this invention and those which are known may be stated generally as follows: The cloth-gripping member or clip of the structure, instead of having its body cast in one piece, has only its jaw-carrying superstructure of cast metal, the basal or platform-forming portion thereof, which runs in frictional contact with the usual raceway of the machine, being a separately formed part, enabling it to be made of steel or other harder and stronger metal. Such superstructure and platform are secured together by pins forming depending pivots for the links of a chain, being withdrawable therefrom by lifting the clip. The chain, from which the clip is thus removable, comprises main links spaced apart to receive and adapted to be engaged by the teeth of the sprocket-wheels for driving the chain and each pivoted on two adjoining pins of two adjoining clips, and it preferably also includes thin links beneath the tooth spaces and each connecting and reinforcing the two pins of each of said members.

In the drawings,

Fig. 1 shows the clip in side elevation and the chain and the race-way of the machine in transverse section;

Fig. 2 is a plan of what is shown in Fig. 1; and

Fig. 3 is an inside or front elevation of the clip and chain.

The raceway 1 shown has a top forward or inner race 2 and an underneath or back race 3, which may be a separate strip suitably held in place by screws 4, there being a channel 5 between the two races in which the chain travels. So much is more or less according to one usual construction; the front

race surface is somewhat lower than the back race surface.

6 designates the mentioned super-structure or body part of the improved clip. It may be of cast iron and is formed as usual with an overhanging fork 6a in the ends of which, on a pin 7, is pivoted the movable jaw 8 of the clip comprising a lower arm 8a, having a rearward projection 8b which carries the usual pivoted feeler 9, and an upstanding arm 8c which, as usual in these machines, is adapted to engage a cam surface (not shown) to move the jaw against the action of gravity from its closed position illustrated to its open position to release and admit the cloth.

10 designates a basal portion, or what I term the platform or grinding member of the clip. It underlies the superstructure and projects forward under the jaw 8 to form the fixed jaw coactive therewith to grip the cloth and it also projects rearward beyond the superstructure. It is formed of some rolled hard sheet metal, as steel, and its forward portion is thickened by an underneath pad so that with this pad resting on the race 2 and the rearward portion of the platform underlapping the race 3 the top of the platform, which here forms from front to rear a single plane, will be horizontal when the clip is in working position on the raceway; this thickening of the platform is here accomplished by forming it of two plates 10a and 10b, the formed superposed.

11 designates the devices for joining together as a unitary structure the superstructure and platform. These are pins shouldered at 11a and their reduced end portions entered upwardly through the platform and superstructure, being secured in place preferably by upsetting or rivetting their upper extremities so that the superstructure and platform are bound rigidly together. Their enlarged or lower end portions form depending pivots.

The chain comprises a series of blocks 12 of hard metal, as steel, each as thick vertically as the space between the bottom of the raceway channel 5 and the underneath surface of the clip platform and each having its ends

rounded in plan, and preferably thin flat links 13. The links 13 are bored with holes 13a whose centers are spaced the same as the pivots 11 of each clip; the links 12 are bored with holes 12a whose centers are spaced apart the same as two adjoining pivots of two adjoining clips. In the preferred construction the links 12 are slotted, as at 12b, to receive the ends of the links 13. The links 12 are spaced so as to admit the sprocket-wheel teeth, which engage them; the links 13 reinforce the pins against the stress of the teeth.

Each clip according to my construction is well adapted to withstand the wear and strain incident to its contact with the races 2 and 3 because its basal portion, upon which such wear and strain principally are imposed, may be formed of sheet material and hence may be made hard and non-fracturable; the sprocket-wheel-engaging portion of the entire structure can be made stronger and more durable than heretofore because its parts are independent of the cloth-gripping elements and can be made especially to withstand the wear and tear incident to their operation; and said structure can in practice be made to have about one-third less weight than the known structure and yet possess equal strength and durability. In the known structures of this class a clip or other part cannot be detached without removing more or less of the entire structure; my construction permits any clip alone to be removed or in fact any part to be removed without disturbing any appreciable portion of the structure. Where the clips are in effect integral parts of the flexible structure, as heretofore (each clip being directly pivoted to its neighbors) limited flexibility resulted because the pivoting points were wide apart; increased flexibility is a feature of my structure because, by alternating and lapping links with the clips, the pivoting points are brought closer together.

Broadly it is not material that the pivots are (as here) projections of or affixed to the clips, since so far as I am aware this is the first instance where in a flexible structure of this class the same is made to comprise a chain complete in itself (as 11—12—13) and a series of clips carried thereby.

Having thus fully described my invention what I claim is:

1. A flexible traveling cloth-gripping structure of a tentering machine comprising a series of links and a series of clips alternating with the links and having downwardly projecting pivots coupling the clips and links together, each clip with its pivot being removable from the links as a unit.

2. A tentering clip comprising a superstructure, a jaw pivoted therein, a sheet metal basal member extending forwardly under the jaw and coactive therewith at its upper

forward surface to grip the cloth and at its under forward surface adapted to bear on a portion of the clip raceway of a tentering machine and also extending rearwardly beyond the superstructure and adapted at its rearward upper surface to bear on another portion of the raceway, and means to secure said superstructure and member together.

3. In combination, a series of spaced links, a series of clips surmounting and alternating with the links, another series of links respectively under the several clips, and pivots connecting each clip and second-named link with the adjacent two first-named links, each first-named link having its end portions slotted and receiving in its slots the adjoining ends of adjoining second-named links.

4. A series of tentering clips each comprising a superstructure, a sheet metal supporting member for said superstructure, pins securing said superstructure and member together and projecting therefrom, and a jaw pivoted to such superstructure and coactive with another member of the clip to grip the cloth, in combination with links pivoted on the projecting portions of the pins and thereby connecting the clips.

5. A tentering clip including a body part, a substantially horizontal sheet metal guiding member affixed thereto and adapted to travel along the raceway of a tentering machine, and a cloth gripping jaw movable between said part and another part of the clip and movably connected to one and coactive with the other of them to grip the cloth.

6. A tentering clip including a body part, a substantially horizontal sheet metal guiding member affixed thereto and having a projecting portion adapted to travel along the raceway of a tentering machine, and a cloth gripping jaw movable between said part and another part of the clip and movably connected to one and coactive with the other of them to grip the cloth.

7. A tentering clip including a body part, a substantially horizontal sheet metal guiding member affixed thereto and adapted to travel along the raceway of a tentering machine, said part and member having forwardly projecting portions arranged one above the other, and a jaw pivoted in the projecting portion of the body part and coactive with the projecting portion of said member to grip the cloth.

In testimony whereof I affix my signature.

JOHN E. PETERSON.
